Application May 20, 1937, Serial No. 143,770

13 Claims. (Cl. 210—1)

This invention relates to a chemical feeding apparatus and an automatic control valve gear therefor, whereby a chemical or the like is injected into a flowing stream of fluid, such as the flow from an oil well, and has for its principal object to provide a simple and relatively inexpensive apparatus which is of positive operation and adapted to function at predetermined intervals.

10 Other important objects of the invention are to provide an automatic control actuated by a fluid pressure medium; to provide a relatively simple adjustment for varying the time interval between the injecting periods; and to provide a 15 toggle mechanism whereby the control valve is instantly moved to and from its respective positions so as to reduce the amount of pressure medium required to operate the apparatus.

In accomplishing these and other objects of the invention, as hereinafter pointed out, we 20 have provided improved details of structure, the preferred forms of which are illustrated in the accompanying drawings, wherein:

Fig. 1 is a perspective view of a chemical feeding apparatus, shown in use for injecting a chemical into the flow line of an oil well and constructed and equipped with an automatic control valve gear embodying the features of the present invention.

30 Fig. 2 is an enlarged sectional view through the chemical feeder, particularly illustrating the control valve gear and the actuating mechanism for operating the pump whereby chemical is periodically injected into the flow line.

35 Fig. 3 is a horizontal section on the line 3—3 of Fig. 2.

Fig. 4 is an enlarged detail section through the control valve and the actuating mechanism therefor.

40 Fig. 5 is a vertical section through the apparatus on the line 5—5, Fig. 4.

Fig. 6 is a horizontal section on the line 6—6, Fig. 4.

45 Fig. 7 is a sectional view of a modified form of control valve and gear.

Fig. 8 is a plan view, partly in section, of the form of the invention shown in Fig. 7.

Fig. 9 is a section through a further modified form of control valve.

50 Fig. 10 is a detail section through a still further modified form of control valve.

Fig. 11 is a section on the line 11—11 of Fig. 10.

Fig. 12 is a section through another form of control valve.

55 Fig. 13 is a detail view of a portion of the

valve spring employed in the form of invention illustrated in Fig. 12.

Referring more in detail to the drawings:

1 designates an oil well having a flow line 2, through which flow from the well is discharged to 5 an oil and gas separator or similar tank (not shown), and wherein the liquid reacts with a chemical to effect breaking of any water and oil emulsion contained in the flow.

In order that the chemical will have as long 10 a contact with the fluid as possible, it is best practice to introduce the chemical directly at the point of the well. Means is, therefore, provided whereby the chemical is introduced in measured amounts, and which permits suitable 15 adjustment whereby the amount of chemical admitted may be regulated substantially in accordance with the volume of well flow. An apparatus constructed in accordance with the present invention is particularly adapted for 20 this purpose and we have, therefore, illustrated and described our improved apparatus for this use, and since it is adapted for other purposes, we do not wish to be limited to the specific application 25 of the invention as described.

Connected into the flow line 2 is a flow regulating valve 3, whereby the flow of the well is limited to a given amount over a certain time period, and connected into the line, in the inlet side of the valve, is a conduit 4, leading from a chemical 30 feeder generally indicated 5, and which is shown as including a substantially cylindrical tank 6 having an annular wall 7 closed at the ends by upper and lower disk-shaped heads 8 and 9. Depending circumferentially of the wall 7 is a 35 cylindrical skirt 10, forming a diaphragm and pump compartment 11 to which access is had through suitable door openings 12, which are normally closed by hinged doors 13. Formed in the top 8 is a fill opening 14 having a depending 40 strainer 15, through which the chemical is poured into the tank. The fill opening 14 is normally closed by a threaded plug 16, having a lateral flange 17 engaging a gasket 18 that is carried on an annular seat 19 to provide a gas-tight 45 joint.

The plug 16 has a pressure release port 20, normally closed by a spring loaded valve 21 to relieve excessive pressures that may occur in the tank. The valve 21 has a port 22 that is closed 50 by an inwardly opening valve 23 which is kept closed by a spring 24, but which is adapted to open in case a vacuum should be drawn in the tank.

Chemical is discharged from the bottom of the 55

5 tank through an outlet pipe 25, leading to the inlet of a pump 26 that is located in the compartment 11. Pressure is maintained in the tank through a conduit 27 that is connected with the top thereof, and which leads from a pressure reducing valve 28 also located within the compartment 11, the flow through the line being controlled by a stop or shut-off valve 29.

10 The mechanism within the compartment 11 is supported upon a frame 30, comprising vertical leg portions 31 and 32, carried on a disk-like plate 33 forming the bottom of the compartment. The leg portions 31 and 32 are provided with foot or flange portions 34 which are secured to the plate 33 by fastening devices, such as bolts, 35. Connected at the top of the leg portions 31 and 32 is an annular ring 36, forming a seat for the periphery of a flexible diaphragm 31. The diaphragm 37 is covered by a cap 38, having an annular flange 39 cooperating with the seat to clamp the periphery of the diaphragm therebetween, the cap being secured by fastening devices, such as cap screws, 40 extending through suitable openings in the flanges and through aligning openings in 20 the diaphragm, as shown in Fig. 2. The central portion of the cap is offset from the attaching portion of the diaphragm to form a diaphragm chamber 41, into which a pressure medium is discharged from a pipe 42 which is connected with 25 the outlet connection 43 of a control valve 44. The inlet 45 of the control valve is connected by a pipe 46 leading from the pressure reducing valve 28. The pressure medium is supplied to the reducing valve 28 by a connection 47 with a 30 trap 48, wherethrough gas is delivered from a supply pipe 49 leading from the casing head 50 of the well 1.

35 The trap 48 includes a cylindrical tank carried by the supporting brackets 51 and 52 whereby the 40 chemical tank is anchored to a post 53, the axis of the tank being arranged vertically. The gas inlet line 49 opens tangentially into the tank at a point below a perforated partition 54 that supports a body of filtering material 55 to filter the 45 gas on its way to the connecting line 47 that is connected with the top of the tank. Any entrained liquid or solid matter carried in the gas gravitates to the bottom of the tank and is drawn off from time to time through a drain valve 56.

50 The diaphragm 37 is caused to pulsate for operating the chemical feeding pump 26, now to be described. The pump 26 is mounted on the plate 33, and includes a block 57 having a piston chamber 58 in which a reciprocating piston 59 is 55 mounted, the piston being operable through a suitable packing gland 60, and has its stem 61 connected by means of a yoke 62 with a diaphragm stem 63. The stem 63 is reciprocably mounted within a threaded bushing 64 that is threaded 60 through a boss 65 on a cross bar 66 of the frame 30. The stem 61 extends freely through a washer 62' fixed to the yoke 62 and carries a nut 61' that engages the upper face of the washer. The stem 61 also carries jam-nuts 61'' that are adjustable 65 to and from the lower face of the washer 62'. Movement of the pump piston can, therefore, be adjusted from maximum, when the nuts 61' and 61'' are tightly engaging the respective sides of the washer 62', to a minimum when the spacing 70 between the nuts is regulated to approach the stroke of the diaphragm. Threaded on the upper end of the stem is a backing plate 67 engaging the under side of the diaphragm. The diaphragm is normally retained in its uppermost 75 position and the piston at the upper end of its

stroke, by a coil spring 68 that is sleeved over the bushing and has its lower end bearing against the boss 65 and its upper end against the backing plate 67. It is thus obvious that when gas is admitted into the diaphragm, through the pipe 42, 5 the diaphragm is moved downwardly against action of the spring 68, and causes the piston 59 to move downwardly in the cylinder, displacing some of the chemical that has been previously drawn therein by the preceding upstroke of the 10 piston.

15 The chemical line 25 is connected to the pump by a valve bushing 69, having an inlet portion 70 controlled by a spring pressed intake valve 71. The valve 71 is normally retained in seated position but is adapted to open on the upstroke of the piston to allow flow of chemical into the piston chamber. As soon as the piston reaches the upper end of its stroke, incidental to action 20 of the spring 68 and release of gas from the diaphragm chamber, the valve 71 is closed by its spring to trap the indrawn chemical in the piston chamber. Upon the downstroke of the piston, responsive to pressure of the gas when admitted to the diaphragm chamber, the chemical is 25 displaced from the pump cylinder through a lateral port 72, leading to an outlet port 73 that is in communication with a valve port 74 in a discharge valve bushing 75. The bushing 75 is threaded into the pump block 57, and has a seat 30 76 for a ball valve 77 to prevent back flow through the pump. Also formed in the bushing, above the valve 77, is a seat 78 that is normally engaged by a spring pressed valve 79. Threaded in the bushing is an outlet fitting 80, having a lateral branch 35 81 connected with the conduit 4, previously mentioned. The fitting 80 is also provided with a suitable pressure gauge 82.

40 The pressure reducing valve 28 is adjusted so that the gas is supplied to the diaphragm chamber at substantially constant pressure, and at sufficient value to effectively operate the diaphragm and piston against action of the spring 68 and the pressure of the fluid moving through the flow line 2. Since gas pressure is supplied to 45 the chemical tank through the pipe 27 to act upon the body of chemical therein, a steady flow of chemical is effected to the pump under an initial pressure, thereby tending to reduce the power required by the pump in injecting the chemical 50 under flow line pressure.

55 The control valve 44 forms an important part of the present invention, and is illustrated in detail in Figs. 4, 5 and 6. The valve includes a valve body 83, having a valve chamber 84 communicating with the pipe 42 through a lateral port 85. Formed in the valve chamber, on opposite sides of the port 85, are annular, oppositely facing shoulders 86 and 87 for supporting valve seat members 88 and 89, having ports 90 and 91 for 60 flow of gas to and from the pipe 42 and through an exhaust line 92. The connection 46 of the control valve communicates with the valve chamber at a point above the valve seat 88, through a port 93, which is under control of a needle valve 65 94. The needle valve has its stem threaded in a lateral extension 95 of the valve body and is manipulated to adjust the effective area of the port 93 by means of a knurled head 96, the needle valve being retained in adjustment by a jam-nut 97 threaded upon the stem and engaging against the lateral extension 95. The exhaust line 92 is threaded into a fitting 98, having a portion 99 projecting into a chamber 100 formed as 70 a part of the valve body, the projecting portion 75

being provided with ports 101 communicating with the interior of the chamber 100. The seat member 88 is of plug-like character and is threaded in the upper end of the valve chamber to seat against the shoulder 86, and the seated end thereof has an annular valve seat 102 encircling a bore 103 which forms a gas passageway communicating through lateral openings 104 with the port 93. The other member 89 is of sleeve-like character and is threaded into the opposite end of the valve chamber, from within the chamber 100, to engage the shoulder 87. The member 89 has an annular valve seat 105 encircling a reduced bore 106 of the sleeve. Located between the seats is a ball valve 107 that is adapted to engage either of said seats under control of a trip mechanism, now to be described.

The trip mechanism includes a flat, bar-like member 108 that is reciprocable in the member 89, and has a reduced rod-like upper end 109 loosely movable through the valve seat to lift the ball from the seat 105 to valving engagement with the seat 102. When the ball is seated on the seat 105, the lower end of the member 108 rests upon the stop 99. The ball valve is normally urged against the rod-like end 109, or the seat 105, by a coil spring 110 that is mounted in the bore of the valve seat member 88, and has one end bearing against the ball and its other bearing against the closed end of the bore. The member 108 has a collar-like guide 111 provided with gas passageways 112. To provide snap action, the member 108 is reciprocated through a trip mechanism 113 that includes a yoke-shaped lever 114, having a hub portion 115 that is pivotally mounted on a cross pin 116 carried by the opposite side walls of the chamber 100 at one end thereof. The yoke also includes spaced arms 117 and 118 projecting from the ends of the hub portion 115, 40 on opposite sides of the member 108, and the free ends thereof are connected by a cross bar 119 at a point spaced inwardly from the ends thereof. The cross bar has a web-like flange provided with a slot 120 to engage the stem of an actuating rod 121, whereby the yoke is rocked upon the pin 116.

The bar member 108 is provided on its lower end with V-shaped grooves 122 and 123 respectively, aligning with grooves 124 and 125 that are provided in the hub portion 115 and the cross bar 119. Seated within the pair of grooves 122—124 and 123—125 are pairs of knife edge bearing members 126—127 and 128—129 of toggles 130 and 131. The toggles 130 and 131 also include springs 132 and 133 shaped to form spaced arms 134 anchored to the ends of the pairs of bearing members and provided with yieldable coil portions 135. The total length of the toggles is greater than the spacing between the bottoms 50 of the grooves 124 and 125 so that the pivotal points of the knife edge bearings are normally offset to one side or the other of a plane extending through the bearing points of the grooves 124 and 125. The actuating rod 136 is carried by the diaphragm backing plate, and projects downwardly through a packing box 137 into the chamber 100 to engage in the slot 120. The rod has stop collars 138 and 139 thereon, adapted to engage the respective sides of the flange of the bar 119, to effect movement of the lever 114 responsive to movement of the diaphragm.

Movement of the lever 114 is limited under throw of the toggles by pads 140 and 141 respectively carried by the top and bottom walls of 75 the chamber 100 and adapted to be engaged by

the cross bar 119. A portion of one side wall of the chamber 100 has a door opening 142, through which access is had to the trip mechanism, the opening being normally closed by a plate 143 secured by fastening devices, such as 5 cap screws, 144. A gasket 145 is also used to form a gas-tight joint.

The chemical tank may be provided with accessories such as a sight glass 146, a gauging rod 147, and a pressure gauge 148.

The tank may also be provided with a gas line 149 that connects the casing head with the bottom of the tank so that gas may be discharged into the chemical to effect agitation thereof, the line 149 being provided with a shut-off valve 15 10 150.

An apparatus constructed and assembled as described operates as follows:

Assuming that a quantity of chemical has been inserted in the chemical tank, and that the lines 20 49 and 149 are connected with the casing head of the well and the line 4 with the flow line 2, gas is supplied from the casing head through the line 49, into the trap 48, where the entrained liquid and solid matter gravitate to the bottom 25 thereof. The separated gas passes upwardly through the filtering material 55 and is discharged through the line 47 to the pressure reducing valve which is set to pass the gas through the lines 21 and 46 at the desired pressure. 30 Pressure of the gas admitted to the tank, through the line 21, is indicated on the gauge 148, and acts on the body of chemical in the tank to effect positive feed thereof through the pipe 25 to the inlet of the pump 26. Should excessive pressures 35 occur in the chemical tank they are relieved through lifting of the valve 21 until the pressure is dropped to the point where the valve spring will effect closure thereof. Likewise should minus pressures occur in the tank, the valve 23 40 will open to allow entrance of air to relieve the vacuum. The stroke of the pump is adjusted by spacing the jam-nuts 61" from the washer of the yoke 62 the desired amount to produce the desired movement of the piston relatively to the 45 full stroke of the diaphragm.

Assuming that the diaphragm and piston are in their uppermost position, as shown in Fig. 2, the ball valve 107 is engaged with the seat 105, closing discharge of gas through the bore 106 50 into the chamber 100, and from the chamber to the exhaust pipe 92. The gas will then flow from the port 93, past the upper seat for the ball valve and through the port 85, through the pipe 42 to the diaphragm chamber. Pressure of gas in 55 the diaphragm chamber will then cause movement of the diaphragm against action of the spring 68. When the washer 62' engages the upper jam-nut the diaphragm becomes effective to move the piston to displace chemical from the 60 piston chamber out through the ports 72 and 73, and past the valves 77 and 79, and through the line 4 into the fluid flowing from the oil well. Downward movement of the diaphragm carries the stop collar 138 on the rod 136 into engagement with the web of the connecting bar on the yoke-like lever, to move the lever downwardly until the contact points of the outer knife bearings have passed the off-center position relatively to the inner knife point bearing members, whereupon stored up tension in the spring will snap the bar member in an upward direction, lifting the ball into engagement with the upper seat, thereby suspending flow of gas through the upper valve seat and opening communication between 75

the diaphragm chamber and the exhaust pipe through the lower valve seat and chamber 100. The spring 68 then comes into play to cause retractive movement of the diaphragm, which carries the piston therewith on the succeeding intake stroke, allowing an additional quantity of chemical to be drawn into the pump cylinder. When the collar 139 engages the yoke-like lever, the lever is carried in an upward direction until the outer knife edge bearings pass dead center position relative to the inner knife edge bearings, whereupon the springs again come into play to cause downward snap movement of the valve control bar, thereby allowing the ball to engage the seat on the exhaust side, and to open communication through the seat on the pressure side to again establish flow of gas to the diaphragm chamber. The apparatus will thus continue to operate at definite, predetermined periods, according to the flow rate of the gas as regulated by the needle valve 94.

The valve illustrated in Fig. 7 includes a valve body 151, having a threaded recess 152 for mounting valve cage members 153 and 154 that are spaced apart by an apertured flange 155 to form an intermediate valve chamber 156 which is located in line with the gas outlet port 157 that is connected with the pipe 42. Formed in the cage members are valve seats 158 and 159, adapted to be alternately engaged by a valve 160 to control flow of pressure medium to and from the diaphragm chamber. The valve has an actuating stem 161 extending upwardly through a cone-shaped vent opening 162 in the upper member to connect with a toggle mechanism 163, later described. The valve also includes a pilot 164 guidingly supported within the inlet port 165. Extending laterally from the side of the valve body is a bore 166, having a threaded outer portion 167 to accommodate the threaded shank 168 of a needle valve 169. The inner end of the bore communicates through a port 170 with the inlet port 171 and through an axial port 172 with the port 165. The needle valve includes a pointed end 173 that is adapted to control the effective area of the port 170 so as to regulate the rate of flow of gas admitted to the diaphragm chamber upon opening of the valve from the seat 159 and closing of the valve on the seat 158. The threaded shank of the needle valve projects from the valve body, and sleeved thereover is a coil spring 174 having one end engaging against the valve body and the other against a disk-like collar 175. The head 176 of the shank is provided with a transverse slot wherein a screw-driver may be inserted to effect rotation of the valve, the spring providing sufficient resistance to retain the valve in adjusted position.

In order that the diaphragm may be automatically operated, the valve 160 is operably connected with the diaphragm backing plate through a trip mechanism, now to be described. Extending upwardly and outwardly from the valve body is a wing 177 that cooperates with a spaced bracket 178 to mount a cross shaft 179. Rockably mounted on the cross shaft 179, on anti-friction bearings 180, is a toggle lever 181 having an arm portion 182 projecting over the valve unit to connect with the valve stem 161. The arm portion 182 has a bore 183 that opens from the rear end thereof and terminates in a ball socket 184.

Formed in the arm portion, below the ball socket, is a keyhole slot 185, having an enlarged portion 186 through which a ball 187 on the valve

stem is inserted into the bore 183 and against the ball socket 184, the stem of the valve passing through the smaller portion 188 of the keyhole-shaped slot as best shown in Fig. 7. The ball is yieldingly retained against its seat by a coil spring 189 inserted in the bore and having one end bearing against the ball and the other against a pin 190 extending across the outer end of the bore. Also rockably mounted on the shaft 179 is a yoke-shaped lever 191, including arm portions 192 extending laterally on opposite sides of the lever 181, and connected at their outer ends by a cross bar portion 193. The cross bar portion 193 is shaped to provide a spring seat 194, and has a cone-shaped opening 195 therein to accommodate the end of a trip pin 196. The trip pin 196 is carried by a ring 197 that is pivotally mounted on anti-friction bearings 198 carried on a cross pin 199, the cross pin 199 being mounted in a yoke-shaped head 200 of the lever 181, as best shown in Fig. 8. Sleeved over the trip pin, and having one end engaging against the spring seat 194, and its other end engaging against the ring 197, is a coil spring 201. The trip pin cooperates with the lever 181 to form a toggle joint which is normally retained in broken position, that is, with the axis of the bearing 198 offset laterally of a plane extending through the spring seat 194 and the shaft 179. In order to control movement of the toggle lever 181, the wing 178 is provided with spaced stops 202 and 203, as shown in Fig. 7, and which are arranged to engage the upper and lower sides of the arm portion 192. The lever 191 has a slotted tongue 204 projecting from the arm 192.

When the diaphragm is in its uppermost position the toggle yoke is engaging the stop 202. In this position the valve plug is engaging the seat 158 to close communication of the diaphragm chamber to atmosphere, and to establish communication between the pressure medium supply line and the diaphragm chamber. Pressure medium will then flow past the needle valve, into the diaphragm chamber. When a sufficient amount of pressure medium has been admitted to the diaphragm chamber so that the pressure acting on the diaphragm overbalances its spring, the diaphragm is moved downwardly, effecting a displacement stroke of the pump piston. The toggle lever swings downwardly toward the lower stop 203. As soon as the spring 201 has passed dead center position relatively to the shafts 199 and 199, the spring becomes effective to throw the lever 181 in the opposite direction, causing closure of the port 165 and opening of the vent port so that the supply of pressure medium is shut off and the pressure medium in the diaphragm chamber is allowed to exhaust to atmosphere. The valve thus will continue to operate in substantially the same manner as the one disclosed in the preferred form.

The valve body in the form of the invention illustrated in Fig. 9 is substantially the same as that illustrated in Fig. 7, however, the valve 205 thereof does not directly control the supply port 206. In this form of the invention, the valve body is provided with a single threaded plug 207, having an external valve seat 208 through which pressure medium from the diaphragm chamber is vented to atmosphere, and on which the valve 205 seats under control of the toggle mechanism.

In the form illustrated in Figs. 10 and 11, the valve actuating lever 209 has a collar portion 210 fixed to a threaded diaphragm actuated rod 211. The lever 209 is secured on the rod by nuts 75

212 and 213 engaging the respective sides thereof. Extending upwardly from the valve body is a guide post 214, carrying a stop 215 to resist movement of a bow-shaped spring 216 during upward movement of the lever 209. When the diaphragm is in its uppermost position, the exhaust port 217 is closed by a valve 218 that is carried by the spring. The pressure medium being admitted through the valve is then effective in building up pressure in the diaphragm chamber. As the diaphragm moves downwardly the lever 209 is moved therewith, storing up tension in the spring 216. As soon as the lever 209 is moved downwardly a sufficient distance, the stored up tension in the bow-shaped spring causes the spring to reverse its curvature and engage the stop 215, thereby providing quick opening of the exhaust port 217 and allowing the pressure medium to exhaust from the diaphragm chamber. As soon as a sufficient amount of pressure has escaped through the port 217, movement of the diaphragm is reversed to again cause seating of the valve so that the pressure medium is again effective in operating the diaphragm.

25 The form of the invention illustrated in Figs. 12 and 13 employs a valve 219 that is carried by a leaf type spring 220, having a deformation 221 to cause snap movement of the valve when the operating lever 222 has moved a predetermined distance.

30 While the structures illustrated in Figs. 9 to 13 inclusive are slightly more wasteful of gas, this wastage is not excessive and they are entirely practicable for the purposes for which they are intended.

35 From the foregoing it is obvious that I have provided an automatic feeder and control valve gear therefor, which may be used for feeding chemical into a flow line, and that the controlling apparatus is of simple and relatively inexpensive construction, and adapted to function at predetermined intervals so as to maintain the feed of the chemicals in proportion to the amount of liquid being discharged from the oil well.

40 What we claim and desire to secure by Letters Patent is:

1. In an apparatus for introducing treating chemical into the flow from an oil and gas well, 50 a chemical supply means, a reciprocatory pump, means connecting the chemical supply means with the pump, means connecting discharge of the pump with the well flow, means for delivering gas from said well to the chemical supply means whereby chemical is delivered to the pump at approximately the pressure of the flow, a diaphragm actuator connected with the pump, means supplying gas to the diaphragm actuator for operating the pump to inject a charge of 55 chemical into the well flow, and means for controlling said gas supply to the diaphragm actuator for automatically effecting reciprocation of the pump.

2. In an apparatus for introducing treating chemical into the flow from an oil and gas well, 60 a chemical supply means, a reciprocatory pump, means connecting the chemical supply means with the pump, means connecting discharge of the pump with the well flow, means for delivering gas from said well to the chemical supply means whereby chemical is delivered to the pump at approximately the pressure of the flow, a diaphragm actuator connected with the pump, means supplying gas to the diaphragm actuator for operating the pump to inject a charge of 65

chemical into the well flow, a valve in said gas supply means for bleeding gas from the diaphragm actuator to effect charging of the pump, and means for actuating the valve responsive to movement of said actuator.

3. In an apparatus for introducing treating chemical into the flow from an oil and gas well, 10 a chemical supply means, a reciprocatory pump, means connecting the chemical supply means with the pump, means connecting discharge of the pump with the well flow, means for delivering gas from said well to the chemical supply means whereby chemical is delivered to the pump at approximately the pressure of the flow, a diaphragm actuator connected with the pump, 15 means supplying gas to the diaphragm actuator for operating the pump to inject a charge of chemical into the well flow, a valve in said gas supply means for bleeding gas from the diaphragm actuator to effect charging of the pump, 20 and means for actuating the valve responsive to movement of said actuator, said connection between the diaphragm actuator and pump having an adjustable lost motion connection for selectively varying the stroke of the pump relative 25 to the movement of the diaphragm actuator.

4. In an apparatus for introducing treating chemical into the flow from an oil and gas well, 30 a chemical supply means, a reciprocatory pump, means connecting the chemical supply means with the pump, means connecting discharge of the pump with the well flow, means for delivering gas from said well to the chemical supply means whereby chemical is delivered to the pump at approximately the pressure of the flow, a diaphragm actuator connected with the pump, 35 means supplying gas to the diaphragm actuator for operating the pump to inject a charge of chemical into the well flow, a valve in said gas supply means for bleeding gas from the diaphragm actuator to effect charging of the pump, 40 and means for actuating the valve responsive to movement of said actuator, and a trip mechanism connected with the diaphragm actuator for operating the valve.

5. In combination with an oil flow line and a gas supply, a chemical feeding means connected with the flow line, pressure actuated means for operating said feeding means, means connecting the pressure actuated means with the gas supply for supplying gas thereto, means regulating flow of the gas to the pressure actuated means, and an operating connection between the gas regulating means and the pressure actuated means for effecting automatic periodic actuation 55 of the feeding means.

6. In combination with an oil and gas well having a flow line and a gas take-off connection, 60 a chemical feeder including a pump, means supplying a chemical to the pump, means connecting the pump with the flow line, pressure actuated means, means connecting the pressure actuated means with the pump, means supplying gas from said take-off connection to the pressure actuated means for effecting operation of the 65 pump, and gas control means in said supply means for effecting periodic actuation of said pump.

7. In combination with an oil flow line and a gas supply, a chemical tank, a pump housing, a 70 pump in the pump housing, means connecting the tank with the pump, a diaphragm chamber in the pump housing, a diaphragm in said chamber, means operably connecting the diaphragm with the pump, means connecting the gas sup- 75

ply with the diaphragm chamber, a valve in said gas supply connecting means for controlling flow of gas to and from the diaphragm chamber, and valve operating means actuated by the diaphragm for operating said valve to effect automatic operation of the pump and periodic injection of chemical into said oil flow line.

8. In combination with an oil flow line and a gas supply, a chemical tank, a pump housing, a pump in the pump housing, means connecting the tank with the pump, a diaphragm chamber in the pump housing, a diaphragm in said chamber, means operably connecting the diaphragm with the pump, means connecting the gas supply with the diaphragm chamber, a valve in said gas supply connecting means for controlling flow of gas to and from the diaphragm chamber, valve operating means actuated by the diaphragm for operating said valve to effect automatic operation of the pump and periodic injection of chemical into said oil flow line, and means connecting the gas supply with the chemical tank to supply the chemical to the pump under pressure of said gas supply.

9. An apparatus of the character described, including a flow line of an oil and gas well, a chemical feeding apparatus, including a tank, pressure actuated means for feeding chemical from the tank into the flow line, means supplying gas from the well to said pressure actuated means, and means supplying said gas to the tank whereby a chemical in the tank is delivered to the pressure actuated means to facilitate injection of the chemical into the flow line.

10. An apparatus of the character described including a flow line of an oil and gas well, a chemical feeding apparatus, including a tank, a chemical pump having connection with the tank, pressure actuated means for operating the pump, means connecting discharge side of the pump with the flow line, means supplying gas from said well to the pressure actuated means to operate the pump, and means supplying said gas to the tank whereby a chemical in the tank is delivered to the pump under pressure to facilitate injection of the chemical into the flow line.

11. In an apparatus of the character described, a pump having a piston, pressure actuated means

for operating the piston, means operably connecting the pressure actuated means with the pump piston, means supplying a pressure medium to the pressure actuated means, a valve controlling flow of pressure medium to the pressure actuated means, means operated by the pressure actuated means for operating the valve to adjust periodic operation of the pump piston, and means in said connecting means for regulating the effective movement of the piston in response to movement of the pressure actuated means.

12. In an apparatus of the character described, a pump having a piston, pressure actuated means for operating the piston, means operably connecting the pressure actuated means with the pump piston, means supplying a pressure medium to the pressure actuated means, a valve controlling flow of pressure medium to the pressure actuated means, means operated by the pressure actuated means for operating the valve to adjust periodic operation of the pump piston, a lost motion connection in said connecting means, and means in said connecting means for regulating the effective movement of the piston in response to movement of the pressure actuated means.

13. In combination with an oil flow line and a gas supply, a chemical tank, a pump housing, a pump in the pump housing, means connecting the tank with the pump, a diaphragm chamber in the pump housing, a diaphragm in said chamber, means operably connecting the diaphragm chamber with the pump, means connecting the gas supply with the diaphragm chamber, a valve in said gas supply connecting means for controlling flow of gas to and from the diaphragm chamber, valve operating means actuated by the diaphragm for operating said valve to effect automatic operation of the pump and periodic injection of chemical into said oil flow line, means connecting the gas supply with the chemical tank to supply the chemical to the pump under pressure of said gas supply, and pressure reducing means in said gas supply connecting means for reducing the pressure of the gas delivered to said diaphragm chamber.
